(57) **CLAIM**

The ornamental design for a wall mount bracket for electronic devices, as shown and described.

DESCRIPTION

FIG. 1 is a top left front perspective view of a wall mount bracket for electronic devices in accordance with the present invention;

FIG. 2 is a top right front perspective view thereof, shown separately to show aspects of the design that are not visible when combined;

FIG. 3 is a bottom left rear perspective view thereof;

FIG. 4 is a left side view of the wall mount bracket for electronic devices shown in FIG. 1;

FIG. 5 is a right side view of the wall mount bracket for electronic devices shown in FIG. 2;

FIG. 6 is a front view thereof;

FIG. 7 is rear view thereof;

FIG. 8 is a top view thereof; and,

FIG. 9 is a bottom view thereof.

The broken lines illustrating an electronic device in FIGS. 1 and 4 are for environmental purposes only and form no part of the claimed design.

1 Claim, 8 Drawing Sheets
